FIG-9

FIG-10

FIG-11

FIG-12

FIG-13

FIG-14

FIG. 1 is a perspective view of a self-priming centrifugal pump showing my new design;

FIG. 2 is a view of one end of the pump shown in FIG. 1;

FIG. 3 is an opposite end view of said pump;

FIG. 4 is a top view of said pump;

FIG. 5 is a bottom view of said pump;

FIG. 6 is a side elevation view of said pump;

FIG. 7 is an opposite side elevation view of said pump;

FIG. 8 is a perspective view of a modification of the pump shown in FIGS. 1 through 7;

FIG. 9 is an end elevation view of the pump illustrated in FIG. 8;

FIG. 10 is a view of the pump of FIG. 8 at the end opposite to that shown in FIG. 9;

FIG. 11 is a top view of the pump of FIG. 8;

FIG. 12 is a bottom view of the pump shown in FIG. 8;

FIG. 13 is a side elevation view of the pump shown in FIG. 8; and

FIG. 14 is an elevation view of the side of the pump of FIG. 8 opposite that shown in FIG. 13.

I claim:

The ornamental design for a self-priming centrifugal pump, substantially as shown and described.
